UNITED STATES PATENT OFFICE.

HARLEY J. MEGLEY, OF CHICAGO, ILLINOIS.

TYPOGRAPHICAL MOLD.

Application filed January 30, 1922. Serial No. 532,656.

To all whom it may concern:

Be it known that I, HARLEY J. MEGLEY, a citizen of the United States, residing at Chicago, in the county of Cook and State 5 of Illinois, have invented a certain new and useful Improvement in Typographical Molds, of which the following is a full, clear, concise, and exact description, reference being had to the accompanying drawings, 10 forming a part of this specification.

My invention relates to type for printing machines and method of and means for making same, and is particularly directed to type for multigraph machines, rotary 15 printing machines and the like.

Type of the class to which my invention is especially directed are now formed in separate blocks, that is, each distinct letter or printing character is carried by its own 20 separate block or base. The opposite sides of these types are provided with nicks, grooves or other retention means for co-operation with means carried by the cylinder or type carrier to hold the type in place 25 upon combining or setting the same up in the desired order in the cylinder or carrier. The formation, setting up and use of such type is tedious, expensive and complicated and a great amount of time and labor is 30 necessary, two persons being usually necessary in the operation of machines employing such type, all of which increases the cost and presents an uncertainty in the results which should be avoided. With the teachings 35 of the prior art, the formation of integral lines of type for use with machines of the multigraph or rotary type is impractical, tedious, expensive and complicated. The lines would have to be formed of a 40 width or height far in excess of that which the printing machine would receive, and these lines would then have to be cut to the desired dimensions and grooved or nicked for attachment to the cylinder or type car- 45 rier.

It is an object of my invention to decrease the cost, tediousness, complications, time and labor in forming, setting up and using the type employed in multigraph machines, rotary printing machines and the like.

A more specific object of my invention is the provision of a novel principle of and means for forming a novel line of type for such machines.

Another object of my invention is the

provision of an improved mold mechanism for casting an integral line of type of the desired height and with the grooves, nicks or other retention means for co-operation with the cylinder or type carrier. This is 60 a highly advantageous feature, in that the formation and setting up or combining of individual or separate type is thereby avoided as is the step of cutting down a line of type of a width or height far in excess of 65 that which the printing or multigraph machine will receive, and the step of grooving or nicking the opposite sides thereof.

A still further object of my invention is the provision of a novel arrangement for 70 ejecting or permitting ejection of a line of type so cast from the mold or casting mechanism.

In accordance with the teachings of my invention, the line of type is cast of the desired height and with the desired grooves, nicks, or the like for mounting in the multigraph or printing machine, integral through a relatively weak or fragile connecting portion with a base portion which makes up the width or height which is formed in the casting mechanism. The line so cast is separated from its base portion by rupturing or breaking the relatively weak or fragile connecting portion upon or after ejection 80 from the casting mechanism giving the desired line ready for insertion into the multigraph machine without the performance of further operations thereupon. While the mold is preferably provided with yielding 85 casting jaws adapted for separation to permit ejection of the line or slug with its reduced connecting portion and grooves or nicks therefrom, I do not intend to be limited to such a mold but contemplate the provision of a rigid molding mechanism for molding the desired line of type and a novel ejecting mechanism for ejecting the same 90 therefrom.

The invention will be more readily understood by reference to the accompanying drawings, in connection with which I will now explain the principle and an embodiment of the invention.

In the drawings: 100
Figure 1 is a front elevational view of the mold wheel of a linotype machine showing a mold embodying my invention in connection therewith;

Fig. 2 is a diagrammatic side elevational 110

view of the mold wheel and associated vise frame;

Fig. 3 is a plan view of the base member of the mold, taken substantially on the line 5 3—3 of Fig. 1;

Fig. 4 is an enlarged front elevational view partially broken away of the mold with the front base plate removed;

Fig. 5 is an enlarged front elevational 10 view of the upper jaw member;

Fig. 6 is a longitudinal sectional view taken on the line 6—6 of Fig. 5 showing the casting face of the upper jaw member;

Fig. 7 is an enlarged transverse section 15 taken on the line 7—7 of Fig. 1;

Fig. 8 is an enlarged transverse section taken on the line 8—8 of Fig. 1;

Fig. 9 is an enlarged fragmentary front 20 elevational view of the mold showing those portions of the jaws between which the wedge or spreading member is inserted;

Fig. 10 is a fragmentary isometric view showing the line of type or slug as it is cast;

Fig. 11 is a fragmentary isometric view of 25 the type line which is inserted in the multigraph machine or rotary press, after separation of the same from the base portion with which it is cast or formed integral;

Fig. 12 is a detail section through one of 30 the wedge members employed for spreading the jaws of the mold;

Fig. 13 is an end view of the mold; and

Fig. 14 is a diagrammatic plan view of 35 a mold showing diagrammatically one manner of ejecting the slug or type carrying block from the mold without spreading or separating the casting faces thereof.

Referring to the drawings, the mold wheel 40 1 is provided with the usual openings in which the type molds are mounted. While the wheel or mold carrier 1 is preferably rotated and moved axially in the usual or any preferred manner to position the mold successively for the reception of a charge of type metal and for ejection, the details and 45 operation of the same may be varied within the scope of my present invention.

Although I have shown only one mold 2 50 in connection with the wheel 1 for carrying out my present invention, it will be understood as this description proceeds that any number of such molds may be combined as desired. The molds 3 are shown as being of the usual formation, while the mold 4 is 55 a blank mold. All are suitably attached to the front face of the wheel or disc 1. In the particular machine in which I have practiced my invention, the type metal is squirted or run into the mold at that point in the 60 cycle of movement thereof in which the mold 2 is positioned in Fig. 1, while ejection is effected at that point in which the blank mold 4 is arranged. While this arrangement may also be varied, it will be obvious 65 from the disclosure that the means of my

invention is adapted for embodiment and the invention practiced with very little change in the casting machines now in general use.

The mold 2 comprises a base member 10 having a front or outer face plate 11 extending over and secured to the outer face thereof as by means of suitable bolts or screws 12, and an associated cap member 16. The upper portion of the outer face of the base member 10 is offset as shown at 13 to receive 70 the depending flange 14 of the inner casting jaw 15.

Spacing pieces or liners 17 and 18 which may be made of various thicknesses and interchanged according to the thickness of the type line or slug desired, are arranged between the opposing faces of the base member 10 and cap member 16 adjacent their opposite ends. The opposite faces of these members which are suitably secured to the base 80 10 as by means of suitable screws 19 are preferably provided with projecting tongues for engagement with grooves 27 in the respective faces of the base member 10 and cap 85 16 to position and maintain the proper positioning of these parts. The inner end of the spacing piece or liner element 17 is provided with notches 21 for the reception of lugs 22 projecting from the adjacent end of a cooperating liner 23. The liner 23 is interchangeable with similar liners of various lengths to secure the desired length of type 90 cast, slug or line, as well understood in the art and is preferably provided with a projecting lip 25 as is the spacer 18 for notching the inner corner of the slug and preventing the formation of burs.

The outer face of the cap member 16, which cap member is held in place by co-operation with the mold wheel upon mounting of the mold thereupon, or by clamping it to the base 10 by means of set screws or in any other desired manner, lies flush with the offset face 13 of the base 10 and thereby provides a surface over which the outer casting jaw 28 is adapted for movement in the plane of movement of the cooperating inner jaw 15.

The outer jaw 28 comprises a longitudinally extending portion 29 having a strengthening rib 30, the contour of which is substantially that of the cap member 16. The opposite ends of the jaw 28 are provided with arms 31 extending inwardly between the offset portion 13 of the base 10 and the inner face of the cooperating plate 11. These arms terminate in projecting stems 32 threaded at their inner ends to receive suitable nuts 33 between which and the base 10 suitable coiled springs 34 are interposed, as shown in Fig. 1. The projecting stems 32 and springs 34 are preferably encased in housings 35 suitably secured to the mold wheel 1 and filled with a lubricant. The opposite ends 36 of the front face of the 115 120 125 130

base 10 project out flush with the outer face of the lower portion of the mold, the thickness of which is greater than the upper offset portion, and define channels 37 through 5 which the arms 31 are guided and the proper positioning of the outer jaw secured and maintained. The rib 30 is provided with guide slots 40 through which the shanks of bolts or screws 41 threaded into the outer 10 face of the cap member 16, extend and serve with the guide means provided for the arms 31 to properly guide and position the outer jaw member.

The proper relative positioning of the 15 jaws 15 and 28 is secured and maintained by guide pins 45 fixed between their ends in the spacing pieces 17 and 18 and projecting at their opposite ends into cooperating openings 46 in the respective jaw members 20 as shown in Fig. 4. The inner or lower portion of the base 10 is provided with bores or sockets 47 internally threaded at their lower ends for the reception of plug members 48. Coiled springs 49 arranged within 25 these bores or sockets 47 between the plug members 48 and the lower edge of the depending flange 14, yieldably maintain the lower jaw 15 in the position shown in Figure 1. The upper jaw 28 is yieldably maintained in the position shown in Fig. 1 by 30 the coiled springs 34. When the jaw members are thus engaged with the opposite faces of the spacing pieces 17 and 18, as shown, they are set for a charge or injection of molten type metal.

As shown in Figure 7 the opposing casting faces of the jaw members 15 and 28 are provided with longitudinally extending tongues or ridges 57 and 58 respectively for 40 forming the desired grooves in the opposite sides of the type line or slug in the casting operation. Obviously, these faces may be formed to provide a plurality of nicks or to give any other desired formation to the 45 type line for mounting and holding the same in the particular rotary press, multigraph machine or the like with which it is to be used. Spaced inwardly slightly from the 50 tongues or ridges 57 and 58 the casting faces of the jaws 15 and 28 are provided with shoulders 60 and 61 which extend into close proximity to form the bottom surface of the type line. The casting face of the 55 jaw 28 is inclined from the reduced mold opening or neck thus formed to the inner face of the jaw. The casting face of the jaw 28 is tapered downwardly from the shoulder 61 to the inner face thereof.

The opposite ends of the inner or upper 60 face of the jaw member 15 are tapered or inclined downwardly to the outer face of the jaw as shown at 52 and the adjacent portions of the jaw 28 inclined or tapered upwardly as shown at 53. Wedge or spreading 65 members 54 carried, in the particular

embodiment shown in proper spaced relation by the vise frame 55 are adapted for cooperation with these tapered portions of the jaws 15 and 28 in this instance upon movement of the mold wheel 1 axially toward the frame 55, to spread or wedge the casting faces of the jaw members apart against the tension of the springs 34 and 49 and permit ejection of the type line or slug from the machine. The wedge members 75 70 are preferably provided with banking shoulders 70 which finally engage the outer faces of the mold jaws to effectively brace the same during the ejecting operation.

The casting jaws of the mold being thus forced or spread apart and the banking shoulders engaged therewith, an ejector blade 72 is projected by suitable ejecting mechanism the details of which per se are 80 85 immaterial in so far as my present invention is concerned, into engagement with the bottom or inner edge of the slug 75 produced, forcing the same out from the mold between a pair of spaced knife members 76 90 95 in the usual manner.

From the foregoing, it will now be apparent that the process practiced with the mold or casting mechanism which I have described, comprises filling or running the 95 molten type metal in between the base and inner jaw on one side and the cap member and outer jaw on the other side, spreading or wedging the jaw members of the mold apart to permit ejection of the type 100 line formed and projecting the ejector blade into engagement with the base or inner edge of the slug and forcing the same out from the mold between the spaced knife members carried by the vise frame to trim the same 105 and remove any burs.

The finished slug comprises the type line or line of type 80 the height h of which is adapted for arrangement in the machine with which it is to be used, joined through 110 a reduced, weakened or relatively fragile connecting portion 81 with a base portion 82 which makes up the width or height which is formed in the casting mechanism. The outer or upper face of the line 80 carries the printing characters or letters 83 formed in the embodiment shown by running the molten metal into the desired line of matrices assembled in the vise frame in the usual manner. The grooves or nicks 84 115 cast in the opposite sides of the type line provide for mounting and holding the same in the multigraph machine, rotary press or the like. The casting of these may be varied, as already pointed out, according to 120 the particular ward or mounting arrangement provided in the machine with which the type is to be used. The height h of the type line from the outer face to the bottom or base 85 which is formed in the cast- 125 130

ing operation, may likewise be varied, as desired. The line 80 so cast is separated from its base portion 82 very quickly and easily by rupturing or breaking the relatively weak or fragile connecting portion 81 upon or after ejection from the casting mechanism, giving the desired line ready for insertion into the multigraph or any other machine with which it is to be used without 10 the performance of further operations thereupon.

While I have shown my invention as practiced in connection with a particular casting machine, it will be obvious that the 15 invention may be practiced with various other machines and various other arrangements than the one shown, whether or not such machines are classed as casting machines.

20 For example, the invention may be practiced with relatively rigid casting jaws as shown in Fig. 14, and the end pieces between which the slug is cast provided with supplemental pieces or extended, as shown 25 at 90 and 91, and adapted for movement lengthwise of the mold. In this case the molten metal is run into the assembled matrices and the line cast to the desired height and with the desired grooves or 30 mounting means therein is then ejected lengthwise from the mold by lengthwise movement of the members 90 and 91.

I do not intend to be limited to the details shown and described, nor to the particular embodiment shown and described, 35 and I intend that modifications in the order practicing the various steps and such other changes as will be apparent at once to those skilled in the art are contemplated within 40 the scope of the appended claims.

I claim:

1. In a mold of the class described, a base member having an offset surface, a plate secured thereto, a jaw member having 45 a depending flange slidably mounted between said offset surface and said plate member, spring means carried by said base member for yieldably maintaining said jaw member in closed position, a cap member, 50 a second jaw member slidably mounted in the plane of movement of said first jaw member, said second jaw member having guide slots cooperable with posts carried by said cap member and projecting arms 55 guided by said base member.

2. In a mold of the class described, a base member having an offset surface, a plate secured thereto, a jaw member having a depending flange slidably mounted between 60 said offset surface and said plate member, spring means carried by said base member for yieldably maintaining said jaw member in closed position, a cap member, a second jaw member slidably mounted in the

65 plane of movement of said first jaw member, said second jaw member having guide openings cooperable with means carried by said cap member, and projecting arms guided by said base member, said arms terminating in stems threaded to receive co- 70 operating nut members, and spring means interposed between said nut members and the mold for maintaining said second jaw in closed position.

3. In a device of the class described, a base member, a cap member, spacing pieces or liners between said base member and said cap member, a pair of relatively movable casting jaws and means carried by said spacing pieces or liners and cooperable with 75 said jaws for maintaining the proper relative positioning of the same.

4. In combination, a pair of jaw members, said jaw members having opposing casting faces and tapered surfaces outwardly 80 beyond said casting faces for cooperation with a spreading member for opening said jaw members.

5. In combination, a mold device including casting jaws adapted to be opened to permit ejection of the casting, spreading means engageable between the jaw members for opening the same independently of the movement of the slug from the mold, and means cooperable with the jaw members for bracing the same during the spreading operation.

6. In a mold of the class described, a base member having an offset surface, a plate secured thereto, a jaw member having a depending flange slidably mounted between said offset surface and said plate member, spring means carried by said base member for yieldably maintaining said jaw member in closed position, a cap member, a second jaw member slidably mounted in the plane of movement of said first jaw member, said second jaw member having guide openings cooperable with means carried by said cap member, and projecting arms guided by said base member, spacing pieces or liners between the base and cap members, and means carried by said spacing pieces or liners and cooperable with the jaw members for positioning the same.

7. In combination, a mold wheel having the usual mold receiving openings, a mold of the usual formation adapted for mounting in one of said openings and for attachment to said mold wheel, and a mold device comprising a body portion having opposed stationary casting faces and a spreadable jaw portion having opposed spreadable casting faces adapted for mounting in another of the usual mold openings of said mold wheel and for attachment to said mold wheel with said first mold in place.

8. In combination, a mold wheel, a mold

of the usual formation adapted for attachment to said mold wheel, and a mold device comprising a body portion and a spreadable jaw portion interchangeable with said first 5 mold.

9. In a mold of the class described, a body portion, a pair of jaw members having opposed casting faces with longitudinal ribs extending therealong for casting a slug 10 having longitudinal grooves in its opposite faces, said jaw members and said body portion being adapted to be assembled and mounted as a unit upon the usual or standard mold wheel.

15 10. In a mold of the class described, a body portion having a surface upon which a jaw portion is slidably mounted, a jaw portion slidably mounted upon said surface, the body portion of the mold being confined entirely to one side of said surface, and the 20 jaw portion confined entirely to the other side thereof.

11. In combination, a mold wheel, a mold device adapted for attachment thereto, said 25 mold device including a body portion constituting a mold for a portion of the opposite faces of the slug, a rectilinearly spreadable jaw portion constituting a mold for another portion of said faces, and means independent 30 of rotation of the mold wheel for spreading said jaw portion to release the slug.

12. In combination, a mold wheel, a vise frame, a mold device attached to the mold wheel, said mold device including a spreadable 35 jaw portion, and a wedge member carried by the vise frame for spreading said jaw portion to release the slug.

13. In a mold of the class described, a body portion, a spreadable jaw slidably 40 mounted upon said body portion, said jaw having an arm projecting from said body portion, a head at the free end of said arm and spring means interposed between said head and the body portion of the mold for 45 moving the jaw to closed position.

14. In a mold of the class described, a body portion, a spreadable jaw, said jaw having an arm projecting from said body portion, a shoulder along said arm and 50 spring means interposed between said shoulder and the body portion of the mold for moving the jaw to closed position.

15. In a mold of the class described, a body portion, a spreadable jaw, said jaw having an arm projecting from said body portion, and a spring coiled about the projecting portion of said arm for moving the 55 jaw to closed position.

16. In combination, a mold wheel, a mold 60 device attached thereto, said mold device including a stationary body portion constituting a mold for a portion of the opposite faces of the slug, a spreadable jaw portion constituting a mold for another portion of

said faces and means for spreading said jaw 65 portion independently of rotation of the mold wheel and of movement of the slug from the mold to release the slug.

17. In combination, a mold wheel, a mold device comprising a stationary body portion 70 constituting a mold for a portion of the opposite faces of the slug and a spreadable jaw portion constituting a mold for another portion of said faces and adapted for attachment as a unit with said stationary body 75 portion to the usual or standard mold wheel.

18. In a mold of the class described, a mold body having stationary faces for casting a portion of the opposite faces of the slug, a pair of spreadable jaw members, said 80 jaw members having opposing faces for casting another portion of the opposite faces of the slug and means engageable between said jaw members to spread the same independently of the movement of the slug from the 85 mold.

19. In a mold of the class described, a body portion, a pair of spreadable jaws mounted upon said body portion, a pair of guide arms projecting from one of said jaw 90 members through the body portion of the mold, and a guide flange projecting from the other of said jaw members between the guide arms projecting from said first jaw member. 95

20. In a mold of the class described, a base member having an offset surface, a plate secured to said base member and a spreadable jaw member having a projecting flange slidably mounted and guided between 100 said offset surface and said plate.

21. In a mold of the class described, a body portion, a spreadable jaw member having a projecting portion slidably mounted in a guideway in said body portion, and a plate member mounted over said guideway and the projecting portion slidably mounted therein and secured to the body portion of the mold. 105

22. In a mold of the class described, a body portion, a pair of spreadable jaws, one of said jaws having a pair of guide arms projecting through guideways in the body portion of the mold, the other of said jaws having a guide portion projecting and 110 guided between the projecting arms of said first jaw portion, and a plate arranged over the projecting arms of said first jaw member and the projecting guide portion of said second jaw member and secured to the body 115 portion of the mold.

23. In combination, a mold wheel, a vise frame, a mold device adapted for attachment to the mold wheel, said mold device including casting jaws adapted to be 120 opened to permit ejection of the slug, a banking block carried by the vise frame, for bracing the jaw members during the 125

ejecting operation and means projecting from said block and engageable between the jaw members for opening the same.

24. In a mold of the class described, a body portion, a pair of jaw members defining a casting space, said jaw members being spreadable in opposite directions from said space to permit ejection of the slug, a liner and means carried by said liner and operable with said jaw portion for maintaining the proper relative positioning of the same during the spreading operation.

25. In a mold of the class described, a stationary body portion constituting a mold for a portion of the opposite faces of the slug, spreadable jaw members constituting a mold for another portion of said faces and wedge means engageable between said spreadable jaw members for spreading said members independently of the movement of the slug from the mold, said stationary body portion holding the slug properly positioned for ejection from the mold.

26. In combination, a mold wheel, a mold of the usual formation adapted for attachment to said mold wheel, and a mold device comprising a body portion and a spreadable jaw portion adapted for attachment to the mold wheel, and for selective use with said first mold.

27. In combination, a mold wheel, a mold of the usual formation adapted for attachment to said mold wheel, a mold device for casting a slug with retention means for securing the same in a type holder or carrier, said second mold device being adapted for selective use with said first mold and having a spreadable jaw portion for permitting ejection of the slug.

40 28. A mold of the class described comprising, a body portion and a jaw portion for casting a slug with retention means for securing the same in a type holder or carrier, said jaw portion being spreadable to permit ejection of the slug and being adapted to be assembled and mounted as a unit with said body portion upon the usual or standard mold wheel.

50 29. In a mold of the class described, a stationary body portion having opposed casting faces constituting a mold for a por-

tion of the opposite faces of the slug, a spreadable jaw portion having opposed casting faces constituting a mold for another portion of said faces and liner means engaging in said body and said jaw portions for spacing the opposite casting faces of said stationary body and said spreadable jaw portions.

30. In combination, a mold wheel having the usual mold receiving openings, a mold of the usual formation adapted for mounting in one of said openings and for attachment to said mold wheel, and a mold device for casting a slug with retention means for securing the same in a type holder or carrier adapted for mounting in another of the usual mold openings of said mold wheel and for attachment to said mold wheel with said first mold in place.

31. In combination, a mold wheel, a mold of the usual formation adapted for attachment to said mold wheel and a mold device for casting a slug with retention means for securing the same in a type holder or carrier, said second mold device being adapted for attachment to the mold wheel and for selective use with said first mold.

32. In combination, a mold wheel, a mold device adapted for attachment thereto, said mold device including a spreadable jaw portion, means for spreading said jaw portion independent of rotation of the mold wheel and of movement of the slug from the mold to release the slug, said spreading means being released to permit closing of said jaw portion to movement of the mold into casting position.

33. In combination, a mold wheel, a mold device adapted for attachment thereto, said mold device including a spreadable jaw portion, wedge means for spreading said jaw portion to release the slug, said wedge means operating to spread said jaw portion when the mold is out of casting position and being released to permit movement of the mold into casting position with said jaw portion in closed condition.

In witness whereof, I hereunto subscribe my name this 28 day of January, 1922.

HARLEY J. MEGLEY.
